GEORGE L. BENNETT, OF CLEVELAND HEIGHTS, OHIO

TREAD FOR SHOE HEELS

Application filed May 11, 1929. Serial No. 362,394.

My invention relates to shoe heels, and more particularly to tread pieces or wearing pieces for the bottom of shoe heels, and means for attaching the same to the heel.

It is the principal purpose of this invention to provide means whereby the tread piece of a heel may be readily attached or removed without the requirement of any skilled work and with a minimum amount of effort.

In shoe heels, particularly on ladies' shoes having high heels, considerable difficulty is encountered in maintaining the wearing surface on the bottom of the heel in good condition. Tread pieces which are secured there-
to wear rapidly, and must be replaced several times during the life of the shoe, or they will become so worn and turned over as to make it very uncomfortable to wear the shoe. With the device contemplated in this application, the matter of replacing a worn tread on the bottom of a heel becomes a simple one that can be done by any person in a minute or two of time.

It is also a purpose of this invention to provide a novel wearing tread which will be able to withstand a much greater amount of wear without losing its shape or becoming so thin as to be useless.

Certain forms of the invention will be described by reference to the accompanying drawings. It is to be understood, however, that the description and drawings are illustrative only, and that the invention is not to be limited except in so far as it is limited by the claims.

In the drawings,—

Fig. 1 is a sectional view of one embodiment of the invention;

Fig. 2 is a section on the line 2—2 of Fig. 1, showing the tread attached to a heel;

Fig. 3 is a sectional view similar to Fig. 1, showing a second form of the invention;

Fig. 4 is a section on the line 4—4 of Fig. 3;

Fig. 5 is a vertical section of a third modification;

Fig. 6 is a section on the line 6—6 of Fig. 5, but with the spread in holding position; and

Figs. 7—11 inclusive are illustrations of the instrument used in attaching and removing the heel tread.

The wearing tread piece in this device is preferably made up of a suitable, relatively hard resilient material, which may be rubber or another substance which will be described more fully hereinafter. In this material I preferably imbed a considerable amount of abrasive substance in the form of acicular particles such as crystals of carborundum of a coarseness approximating No. 40 grain. These particles are preferably disposed in the resilient material with their long axes directed at right angles to the wearing surface of the tread. I also prefer to add a considerable portion of these particles to the lower part of the tread, decreasing the amount toward the top of the tread, thus leaving the upper portion with little or practically none of the hard particles therein. This serves to give greater wearing qualities to lower part of tread. Also it makes for maximum resiliency of the attaching portion thereof which is of considerable advantage.

High grade rubber is suitable for this purpose if properly vulcanized. However, I prefer to use a high grade gelatin, which is suitably hardened and waterproofed by proper chemical treatment so as to bring it to the hardness of high grade sole leather. This material has a considerable advantage in that it adheres well to the abrasive material and has a greater firmness than rubber.

Referring now to Figs. 1 and 2, I show a heel shell 10, which in the form shown is of metal, although it may be of any other suitable material, and this heel is formed in the bottom with a suitable recess 11 to receive the upper portion of the tread. A lining such as indicated at 12 is spot-welded or otherwise secured within the heel 10, and this lining, as shown, is corrugated to form the inwardly extending portions 13 and 14, which form restrictions in the cross-sectional size of the recess 11. The tread 15 is reduced as shown at 16 so as to fit within the recess 11, and carries a plurality of securing members, such as indicated at 17 and 18, which, as shown, extend into the tread so as to be firmly secured thereto, and then extend upwardly a distance sufficient to bring the tread tightly up into the heel before the

tops of the members 17 and 18 engage the bottom of the recess 11.

Owing to the resiliency of the tread 15, and, if desired, the resiliency of the members 17 and 18, these members normally, before the insertion of the tread, extend toward each other at the top, lying in substantially the position shown in dotted lines in Fig. 2. A spreader piece 19, substantially in the shape of a Maltese cross, is provided for forcing the members 17 and 18, of which there are preferably four, outwardly into locking engagement with the member 12 of the shoe heel. This spreader piece is preferably constructed of a metal which when bent tends to remain where it is bent, and has but little elasticity which tends to return it to its former position. This spreader, before the tread is attached, lies in the position shown at 20 in dotted lines in Fig. 2 and has the laterally extending arms thereof directed upwardly and outwardly to permit the members 17 and 18 to extend toward each other and be inserted in the shoe heel.

Now, however, after the tread is inserted in place, a sharp instrument may be extended upwardly through the slit 21 provided in the bottom of the tread to force the spreader 19 upwardly into the full-line position shown in Fig. 2. This, of necessity, forces the members 17 and 18 outwardly to cause them to interlock with the corrugations 13 and 14 formed in the member 12. This firmly holds the tread in position until such time as it is desired to remove it, at which time an instrument similar to the one first used, but somewhat longer, may be inserted through the slit 21 to bend the member 19 upwardly and to the dotted-line position shown at 22 in Fig. 2, so that the members 17 and 18 may again move toward each other and permit detachment of the tread from the heel.

The form shown in Figs. 3 and 4 utilizes a member 12', which is secured to the shoe heel in a manner similar to that in which the member 12 is secured to the shoe heel, and this member is provided with a shoulder at 23 which functions in connection with certain securing means which will now be described.

The tread is preferably provided with laterally extending, rigid rods, such as indicated at 24 and 25, imbedded in the material thereof but not adhering thereto, and having transverse slots at 26 and 27 into which the material of the tread is molded. In the molding of this type of heel, the inner ends of these elements 24 and 25 are brought fairly close together, and a recess 28 is provided in the tread, which recess contains a spreader element 29 having an enlarged head 30 and a stem portion 31 of a slightly less size. Above and below the recess 28, the tread is provided with slits, as at 21' and 32. The member 12' is also provided with an upward-

ly extending recess 33, the purpose of which will now be explained.

When the tread is to be inserted in the heel, the member 29 is in the lowermost position in the recess 28, so as to permit the members 24 and 25, of which there are four, to be retracted by the resiliency of the tread piece. This tread piece as shown is cut away as shown in Fig. 3 to avoid too great a resistance to the spreading action of members 24 and 25. After the tread is inserted to its fullest extent, a sharp instrument may be passed upwardly thru the slit 21' to force the member 29 up between the inner ends of the bars 24 and 25 and spread them out over the shoulders 23, and thus lock the tread in place. The member 29 is preferably forced upwardly just to the position shown in Fig. 4, after which it is retained in this position by the inner ends of the bars 24 and 25 engaging against the reduced portion 31 of the member 29. This serves to hold the tread in position, and the conical top 30 of the member 29 prevents this member from working farther upward after the affixing instrument is removed. The material of the tread is, of course, distorted, as shown in Fig. 3, by the forcing of the members 24 and 25 outwardly.

Now, when it is desired to remove the tread, an instrument is inserted to drive the member 29 up into the recess 33, and this will permit the resiliency of the tread member to draw the members 24 and 25 back together, so that they clear the shoulder 23 and permit the tread to be removed.

In the form shown in Figs. 5 and 6, the heel and tread are of substantially the same structure as in the other forms, but the member 12'' tapers outwardly toward the inner end of the recess that it forms, and the tread piece is provided with an enlarged hollow recess 35 that is adapted to receive a spreader 36, which will now be described.

This spreader is preferably made of a disk of metal, which is cut inwardly from its outer edges and then has alternating rim portions turned up and down to provide flanges for engaging against the thin outer wall 37 of the tread.

An open top is provided at 38 in the tread, thru which this disk may be inserted into the recess 35. This disk functions in the same manner as the spreader 19; that is to say, a sharp instrument is inserted after the tread is in place to remove the disk from the straight-line position shown in Fig. 5 upwardly in a manner similar to the movement of the member 19 shown in Fig. 2 thus spreading the flanges outwardly, which causes the tread to spread and wedge itself within the recess formed by the member 12''. Then, when it is desired to remove the tread, the disk is distorted upwardly so that it will withdraw its flanges and permit the tread to be removed from the heel. The material of the

tread surrounding the heel is preferably slotted as shown at 39 to reduce the resistance to the spreading action of the disk.

In all of these devices, it will be noted that the attachment of the tread depends not upon proper nailing and proper alignment with the heel, but instead, the tread is made of the proper shape so that it must align with the heel when inserted, and the only operation necessary to secure it or remove it is the insertion of a shorter or longer, sharp instrument through the slit provided in the bottom of the tread to move the spreader element upwardly, first, into locking position when the tread is attached, and farther upwardly into releasing position when the tread is to be removed.

The instrument used in affixing or releasing the tread is shown in various forms in Figs. 7-11 inclusive. The slit through the base of the tread must of course close up tightly after the tread is affixed to the heel to prevent foreign matter such as water from getting within the tread. The instrument therefore is preferably a long thin two edged blade with a fairly sharp point. The affixing instrument preferably is of just the proper length so that when blade 40 (see Fig. 11) has forced the spreader into locking position, the base 41 is pressed against the bottom of the tread. The releasing instrument must be sufficiently longer than the affixing instrument to force the spreader up far enough to release the tread. Fig. 10 illustrates an instrument which is used for releasing.

It is of considerable aid to have the two instruments combined and also to have means whereby to support the tread for affixing it to the heel. In Figs. 8 and 9 I show a form which embodies these features. In this form the base 42 has thereon a releasing blade 43 and an affixing blade 44 of substantially the same length as 43. Encircling the blade 44 is a coiled spring 45 which supports a cup-shaped tread supporting member 46 that preferably has the flange just long enough so that when the blade 44 is forced into the tread far enough to force the spreader into tread affixing position, the flange will rest on the base 42.

In the preferred form of affixing and releasing means, however, I utilize a single lenticular blade 47 such as described hereinbefore and shown attached to a base 48. This blade is long enough when used with the base 48 alone to release the spreader. A spring 49 and cup-shaped member 50 are secured together and member 50 is apertured so that they may be fitted on the blade 47. The flange or member 50 is long enough so that when the member 50 is pressed down into engagement with the base 48, the blade 47 extends above member 50 a sufficient distance to force the spreader into affixing position.

The construction of the slit in the bottom

of the tread piece is preferably made so as to prevent any foreign matter or particles from getting into the interior thereof. That is to say, the slit is self closing or substantially so with the affixing instrument of the shape described. It is evident that it will not greatly distort the material of the tread when inserted to affix the tread. As a result the self closing slit will thereafter close and prevent moisture etc. from entering the recess by way of this slit.

From the above description, it is thought that the construction and operation of this device will be clear to those skilled in this art, and, having thus described my invention, so what I claim as new and desire to secure by Letters Patent is:

1. A device of the character described comprising a shoe heel having a recess in the bottom thereof, said recess having a portion thereof above the bottom of the heel larger in cross-section than another portion thereof intermediate said first-named portion and the open end of said recess, a tread piece having a portion insertible in said recess, and means carried by said insertible portion expandable into said larger portion of said recess to secure said tread in place.

2. In a device of the character described comprising a shoe heel having a recess in the bottom thereof, said recess having a portion thereof above the bottom of the heel larger in cross-section than another portion thereof intermediate said first-named portion and the open end of said recess, a tread piece having a portion insertible in said recess, and means carried by said insertible portion expandable into said larger portion of said recess to secure said tread in place, said tread having means whereby to release said expandable means to permit removal of the tread from the heel.

3. A device of the character described comprising a shoe heel having a recess in the end thereof, said recess having a restricted portion spaced from its base, a tread piece having attaching means normally insertible in said recess past said restricted portion, and means for spreading said first-named means to lock the tread piece to the heel.

4. A device of the character described comprising a shoe heel having a recess in the end thereof, said recess having a restricted portion spaced from its base, a tread piece having attaching means insertible in said recess past said restricted portion, and means for spreading said first-named means to lock the tread piece to the heel, said last-named means including a spreader element carried by said tread piece.

5. A device of the character described comprising a shoe heel having a recess in the end thereof, said recess having a restricted portion spaced from its base, a tread

- piece having attaching means insertible in said recess past said restricted portion, and means for spreading said first-named means to lock the tread piece to the heel, said last-named means including a spreader element carried by said tread piece movable in one direction to spread said first-named means and upon further movement permit its return to normal position for removal of said tread piece.
6. A device of the character described comprising a shoe heel having a recess in the end thereof, said recess having a restricted portion spaced from its base, a tread piece having attaching means insertible in said recess past said restricted portion, and means for spreading said first-named means to lock the tread piece to the heel, said last-named means including a spreader element carried by said tread piece, said tread having provisions for the insertion of a tool to operate said spreader.
7. A device of the character described comprising a shoe heel having a recess in the end thereof, said recess having a restricted portion spaced from its base, a tread piece having attaching means insertible in said recess past said restricted portion, and means for spreading said first-named means to lock the tread piece to the heel, said last-named means including a spreader element in said tread piece and said tread piece having a slit in the bottom thereof for insertion of a tool to operate said spreader.
8. A device of the character described comprising a shoe heel having a recess in the end thereof, said recess having a restricted portion spaced from its base, a tread piece having attaching means insertible in said recess past said restricted portion, and means for spreading said first-named means to lock the tread piece to the heel, said last-named means including a portion movable toward the bottom of said recess to spread said first-named means and movable further toward the bottom to permit retraction of said first-named means and removal of said tread piece.
9. A tread for shoe heels and the like comprising a body formed to fit a shoe heel and having an upwardly extending portion for insertion in a recess in the bottom of a shoe heel, said upwardly extending portion carrying means that may be spread laterally to secure the tread in a recess, and means for spreading said first-named means.
10. A tread for shoe heels and the like comprising a body formed to fit the contour of a shoe heel and having an upwardly extending portion for insertion in a recess in the bottom of a shoe heel, said upwardly extending portion carrying means that may be spread laterally to secure the portion in the recess, and a spreader element engaging said means.
11. A tread for shoe heels and the like comprising a body formed to fit a shoe heel and having an upwardly extending portion for insertion in a recess in the bottom of a shoe heel, said upwardly extending portion carrying means that may be spread laterally to secure the portion in the recess, and means for spreading said first-named means, said body having a slit in the bottom of said tread for the insertion of a tool.
12. A tread for shoe heels and the like comprising a body formed to fit a shoe heel and having an upwardly extending portion for insertion in a recess in the bottom of a shoe heel, said upwardly extending portion carrying means that may be spread laterally to secure the portion in the recess, and a spreader element engaging said means, said tread having provisions for insertion of a tool to operate said spreader element.
13. A device of the character described comprising a shoe heel, a tread piece, inter-engaging means on said heel and tread piece for holding the same together, and means inserted into said tread piece and heel for holding said interengaging means against separation, said last named means being movable into said heel to permit release of said interengaging means.
- In witness whereof, I hereunto subscribe my name this 10th day of April A. D. 1929.
- GEORGE L. BENNETT.
